UNITED STATES PATENT OFFICE.

JACOB W. LATTIG, OF ROCHESTER, NEW YORK, ASSIGNOR TO AMERICAN AUTOMATIC TELEPHONE CO., OF ROCHESTER, NEW YORK, A CORPORATION OF NEW YORK.

IMPULSE-TRANSMITTER.

1,030,412.

Specification of Letters Patent. Patented June 25, 1912.

Application filed May 18, 1907. Serial No. 374,029.

To all whom it may concern:

Be it known that I, JACOB W. LATTIG, of Rochester, in the county of Monroe and State of New York, have invented certain new and useful Improvements in Impulse-Transmitters; and I do hereby declare the following to be a full, clear, and exact description of the same, reference being had to the accompanying drawings, forming a part of the specification, and to the reference-numerals marked thereon.

The present invention has for its object to provide an apparatus for interrupting the flow of current over an electric circuit, either by opening a closed circuit or closing an open circuit which is capable of being employed for despatching signals in connection with automatic telephone, fire alarm, telegraph or other systems in which one or more impulses of current, or a group of impulses control the conjoint operation of other mechanism forming a part of such system.

To these and other ends the invention consists in certain improvements and combinations of parts all as will be hereinafter more fully described, the novel features being pointed out in the claims at the end of the specification.

In the drawings: Figure 1 is a view in elevation of an apparatus constructed in accordance with the invention. Fig. 2 is a top plan view, shown with the casing broken away. Fig. 3 is a vertical sectional view taken on the line 3^x—3^x of Fig. 1. Figs. 4 and 5 are sectional views taken on the lines 4^x—4^x and 5^x—5^x, respectively, of Fig. 3. Fig. 6 is a detail view of the retarding devices. Fig. 7 is a similar view illustrating the adjustment of one of the contact fingers taken on the line 7^x—7^x of Fig. 4, and Fig. 8 is a detail sectional view showing the construction of the circuit controlling member.

Similar reference numerals in the several figures indicate similar parts.

An impulse transmitter constructed in accordance with the present invention comprises generally an indicator or setting member which may be operated manually to travel a predetermined distance when released and a member actuated by suitable driving devices, impelled during the return of the indicator to its initial position to ro-

tate such member to open and close an electric circuit a given number of times, corresponding to the distance through which the indicator is permitted to travel.

The operating parts of the apparatus, shown as the preferred embodiment of the invention, are arranged within a cylindrical casing 1 and are mounted upon a frame comprising a back plate 2 and a front plate 3, said plates being held in spaced relation by posts 4, struck up by means of dies from the back plate, which have inwardly turned extremities receiving the screws 5, passing through apertures in the plate 3. The apparatus is adapted to be attached to a suitable support by screws 6 extending through perforations in the back plate in alinement with notches or recesses 7, in the front plate, which permit access to the heads of the screws, as shown in Fig. 4. Projecting rearwardly from the back plate are small spacing lugs 8 designed to separate the frame a short distance from the support, as shown in Figs. 2 and 3.

Journalized centrally on the frame is a driving shaft 9 to which is connected one end of a spring 10, arranged within a casing 11 to which its outer end is attached, said casing having an outwardly flaring bottom edge 12 resting against the outer face of the plate 3 and centered thereon by a ring 13 within which it is held in adjusted position by screws 14, as shown in Figs. 3 and 4. By this arrangement the tensions of the spring may be readily adjusted by rotating the casing in one direction or the other. On the inner end of the shaft 9 is a laterally projecting finger 15 co-operating with a projection 16 on the plate 2 to limit the rotary movement of the shaft in the direction in which it is impelled by the tension imparted to the spring 10, when the devices which ordinarily limit the rotation of the shaft 9 are detached therefrom.

The shaft 9 constitutes a driving element and at one side of the latter is a driven element, or arbor 17, carrying at its end a circuit controlling member 18, composed of conductive and non-conductive portions, as will be further described, with which co-operate the springs or wipers 19 and 20, supported in holders 21 and 22, of insulating material, secured to outwardly extend-

ing lugs on the plate 3, said wipers forming the terminals of conductors 19^a and 20^a, as shown in Fig. 4. The driven arbor is connected by a suitable train of gearing whereby its speed of rotation is increased relatively to that of the driving shaft so that the movement of the latter through a comparatively small angle will cause a complete rotation of the member 18 to both open and close the circuit between the fingers or wipers 19 and 20.

To insure the arresting of both the member and indicator in their normal positions these parts are arranged to coöperate, the former constituting a stop for limiting the movement of the latter to insure the indicator being arrested in its initial position after each operation, while the indicator itself, when returned to its position of rest, serves to lock the circuit controlling member in its proper position relatively to the wipers 19 and 20.

In the present instance, the indicator is shown as a disk 23 which is seated on a hub 24 secured to the driving shaft 9 and held against rotation thereon by means of a lug or projection 25 extending into a slot formed in said hub. The indicator is removably attached to the shaft by a thumb nut 26 and a spring washer 27. On the rear face of the indicator is a stop pin 28 which, when the indicator is in its normal position, engages the member 18 to limit the rotary movement of the driving shaft 9 in one direction. Owing to the smallness of the parts, the rapidity with which they operate and the looseness which it is desirable to provide in fitting them to both reduce their cost of manufacture and the labor in assembling them, it is preferable to provide the circuit controlling member 18 with a cam shaped projection 29, having an operating face arranged relatively to the line of division between the conducting and non-conducting portions of said member, which is so shaped that in case the latter is overthrown beyond its proper starting position, it will be engaged by the stop pin 28 to retract the member 18 a partial rotation, thus insuring the circuit between the two wipers 19 and 20 being closed and thus obviate any inaccuracy in the operation of the device in case there is undue play, or back lash, in the train of driving gears due to wear of the parts or other causes.

In order to conveniently operate the disk 23 to despatch a desired predetermined number of impulses of current, the indicator or setting member is provided upon its face with a plurality of circumferentially arranged apertures which are spaced equidistantly and may be numbered consecutively, as indicated in Fig. 1, or provided with other suitable index characters. Coöperating with these apertures is a handle piece

30 connected to the apparatus by a chain 31, the end of which may be secured beneath the thumb nut 26. The tip of the handle piece, indicated by 32, is adapted to project beyond the inner face of the disk, as shown in Fig. 3, in position to coöperate with a stationary stop 33, projecting outwardly from the plate 3, which is arranged relatively to the driven arbor 17 and the member 18 thereon to arrest the movement of the indicator or setting device, when the latter is set manually by rotating it in the direction indicated by the arrow in Fig. 1. This movement of the indicator carries the stop 28 a sufficient distance away from the member 18 to permit the latter to be rotated the desired number of times before the disk shall have been returned to its normal position by the spring 10. For instance, if the pin 30 should be inserted in the aperture 85 bearing the index 1 and the indicator 23 moved in the direction indicated by the arrow, the angle of movement thereof would be comparatively slight and the distance would be sufficient only to permit the member 18 to make one complete rotation, but if the pin should be placed in the last aperture, bearing the index 50, the disk could be rotated almost a complete revolution before being arrested by the engagement of the end 95 32 of the pin with the stop 33, and when released by the operator the train of gearing would cause the member 18 to make exactly fifty complete revolutions during the retrograde movement of the setting member 23.

The driving connections between the shafts 9 and 17 comprise the gear wheel 33, journaled loosely on the shaft 9, which coöperates with the pinion 34 on the arbor 35, also carrying the gear wheel 36, coöperating with the pinion 37 on the arbor 38. The latter also carries the gear wheel 39 meshing with the pinion 40, on the driven shaft 17. In order to permit the free rotation of the driving shaft 9 in one direction during the movement of the indicator or setting member into an operative position, a ratchet connection is arranged between it and the gear wheel 33, comprising the tooth disk 41, secured rigidly to said shaft, with which coöperates the spring pawl 42 carried on the gear wheel 33. The speed of rotation of the driven shaft is made constant by a governor comprising loosely pivoted friction members 43, carried on a disk 44 connected to the shaft, which are thrown outwardly by centrifugal force into engagement with the annular wall of a casing 45 attached to the rear plate 2, as shown in Figs. 3 and 6.

The circuit controlling member may be made in any desired manner, but the form which it is preferable to employ is the one illustrated in detail in Fig. 8 comprising two frusto-cylindrical portions 46 and 47, 130

the former of metal and the latter of insulating material, both of which are perforated and are fitted tightly to a sleeve of insulating material 48 threaded on the arbor 5 17 and locked thereon by the cam plate 29. This arrangement provides a diagonal line of separation between the conductive and non-conductive portions of the member 18 permitting the contact springs or wipers 19 10 and 20 to engage therewith at all times, the circuit between them being broken when the metallic portion 46 thereof is rotated out of engagement with one of the wipers. This construction of the circuit controlling member 15 permits the length of time during which the circuit, between the wipers, is opened to be varied by adjusting one of the wipers laterally to cause it to engage with the portion 46 during major or minor portions of 20 the rotation of the member 18 which is accomplished by varying the point of contact of the wiper 20 with the curved edge of the portion 46. To facilitate this adjustment the wiper 20 is provided with an elongated 25 aperture 49 through which one of the binding screws 50, on its holder 22, passes. This feature of varying the length of time a circuit is opened independently of the rotation of the armature is particularly advantageous 30 when the device is employed in connection with other apparatus having devices, such as electromagnets, which are energized and deenergized by the opening and closing of their circuits, as it permits the 35 impulse periods to be regulated to accommodate magnets whose magnetic permeability varies.

The frame plates 2 and 3 are preferably made circular in form and slightly smaller 40 in diameter than the indicator disk 23 to permit the outer edge of the cylindrical shell or casing 1 to lie beneath the latter. The casing 1 is provided with inwardly projecting curved shoulders 51 situated in rear of 45 the plate 3 and at a slight angle thereto, so that when rotated thereon the casing will be moved rearwardly into engagement with the face of the support to which the apparatus is connected. In order to permit the 50 casing to be removed, when the indicator 23 has been detached by the removal of the nut 26, the plate 3 is provided with suitable notches 52 in its periphery with which the shoulders 51 may register, this manner of 55 attachment permitting ready inspection of operating parts of the mechanism.

I claim as my invention:

1. In an impulse transmitter, the combination with circuit terminals, a movable controller coöperating with them, each complete movement of which successively breaks and makes an electric circuit leading through the terminals and means for operating the controller, of an adjustable device for actuating 60 said means to cause the controller to be op-

erated a predetermined number of times, a stop on said device engaging the controller to limit the movement of the device in one direction and means for restoring the latter to its normal position after each operation. 70

2. In an impulse transmitter, the combination with circuit terminals and a movable controller coöperating with them, each complete movement of which successively breaks and makes an electric circuit leading through 75 the terminals, of a setting device adjustably supported and movable relatively to the controller for governing its operation for a predetermined number of movements, coöperating stops on the controller and setting devices for arresting both of said parts in 80 their normal positions and mechanism for operating the controller and restoring the setting device.

3. In an impulse transmitter, the combination with circuit terminals and a revoluble controller for making and breaking a circuit leading through them once for each complete rotation, of a setting device movable relatively to the controller and capable of 90 being adjusted in various positions to cause the controller to be rotated one or more times, devices for driving the controller and coöperating stops on the controller and setting device for arresting both of said parts 95 in their initial positions.

4. In an impulse transmitter, the combination with the circuit terminals and a movable controller coöperating with said terminals to interrupt an electric circuit leading through said terminals, of an operating mechanism together with means for setting said operating mechanism to varying positions, means for returning said mechanism to initial position, means for connecting 100 said controller with said operating mechanism during the return movement thereof, and coöperating stops movable with said controller and operating mechanism respectively for arresting said operating mechanism in its initial position. 105

5. In an impulse transmitter, the combination with the circuit terminals and a revoluble controller for interrupting a circuit leading through said terminals, of an operating mechanism, together with means for setting said mechanism at varying positions, said operating mechanism being movable 115 relatively to the controller in one direction of movement but adapted to be operatively connected therewith upon its return movement to rotate said controller varying distances, means for returning said operating mechanism to normal position, and coöperating stops movable with the controller and with said operating mechanism for arresting said operating mechanism in its initial position. 120

6. In an impulse transmitter, the combination, with the circuit terminals, a driving 130

shaft, a driven arbor and a controller on the latter coöperating with the terminals for interrupting a circuit leading through the same, an operating mechanism adapted to be set to varying positions, together with means for returning the same to initial position, said operating mechanism being movable with respect to said arbor while being set and adapted to be operatively connected therewith upon its return movement to rotate said controller varying distances, a rotatable stop movable with the controller, and a second stop movable with the operating mechanism, said stops coöperating with each other to arrest the operating mechanism in its initial position.

7. In an impulse transmitter, the combination with circuit terminals, a driving shaft, a driven arbor and a controller on the latter coöperating with the terminals for interrupting a circuit leading through them, of a stop on the controller, a setting device attached to the driving shaft coöperating with the controller stop and limited in its movement in one direction thereby, a handle piece adapted to coöperate with the setting device at various points for rotating it in the opposite direction, a relatively stationary stop coöperating with the handle piece and driving devices between the shaft and arbor.

8. In an impulse transmitter, the combination with circuit terminals, a driving shaft, a driven arbor and a controller, coöperating with said terminals comprising a conductive portion, a setting device on the shaft and a stop on the arbor coöperating therewith to limit the movement of the setting device in one direction and arrest the controller, said stop being arranged relatively to the conductive portion of the controller for locking it in its initial position after each movement, means for rotating the driving shaft which coöperates with the controller stop to limit the movement of the shaft in one direction, a motor spring which is placed under tension by the rotation of the shaft in the opposite direction and devices actuated by the spring for driving the arbor.

9. In an impulse transmitter, the combination with circuit terminals, one of which is adjustable, of a movable controller coöperating with the terminals for interrupting a circuit leading through them comprising a conductive portion having an edge which passes into and out of engagement with one of the terminals and is disposed at an angle to its direction of movement and means for moving the controller.

10. In an impulse transmitter, the combination with circuit terminals, of a revoluble controller comprising a conductive portion adapted to coöperate with said terminals to alternately make and break a cir-

cuit leading through them, said portion having an edge coöperating with one of the terminals and arranged at an angle to its axis of rotation and means for rotating the controller.

11. In an impulse transmitter, the combination with a frame, a driving shaft and an arbor journaled thereon, circuit terminals located on the front of the frame and a controller mounted on the arbor and coöperating with the terminals for interrupting a circuit leading through them, of a plate detachably mounted on the driving shaft and covering the underlying parts of the instrument and driving connections between the shaft and arbor.

12. In an impulse transmitter, the combination with a frame, a driving shaft projecting outwardly therefrom and an arbor also journaled on the frame, circuit terminals located on the front of the frame and a controller mounted on the arbor and coöperating with the terminals for interrupting a circuit leading through them, of a driving connection between the shaft and arbor, a motor spring connected to the shaft and means arranged on the front of the frame for adjusting the tension of the spring and a face plate for revolving the shaft which is detachably connected thereto and covers the underlying parts of the instrument.

13. In an impulse transmitter, the combination with a frame, a driving shaft projecting outwardly therefrom and an arbor also journaled on the frame, circuit terminals located on the front of the frame and a controller mounted on the arbor and coöperating with the terminals for interrupting a circuit leading through them, of driving connections between the shaft and arbor, a motor spring connected to the shaft, a casing for the spring which is also connected thereto and is adjustably mounted on the front of the casing, a cover plate for the aforementioned parts detachably connected to the shaft and means separate from the cover plate for limiting the movement of the shaft under the tension of the spring when the cover plate is removed.

14. In an instrument of the character described, the combination with a frame adapted to be secured to a suitable support comprising a circular portion, of a casing surrounding the latter having one edge adapted to rest upon the support and interlocking shoulders on the casing and frame which are capable of detachment by a rotary movement of one of the parts relatively to the other.

15. In an impulse transmitter, the combination with a circular frame, circuit terminals thereon, a controller coöperating with the latter for interrupting a circuit leading through them and a driving shaft

journaled centrally on the frame, of a cylindrical casing surrounding the latter, interlocking connections, between the casing and frame which are capable of disengagement by a rotary movement of one of the parts relatively to the other, a cover plate overlapping the rim of the casing and de-

tachably connected to the driving shaft and driving connections between the latter and the controller.
